UNITED STATES PATENT OFFICE.

REYNOLD JANNEY, OF NEW YORK, N. Y., ASSIGNOR TO THE WATERBURY TOOL COMPANY, OF NEW BRITAIN, CONNECTICUT, A CORPORATION OF CONNECTICUT.

UNIVERSAL JOINT.

1,119,608.

Specification of Letters Patent.

Patented Dec. 1, 1914.

Application filed September 19, 1912. Serial No. 721,195.

To all whom it may concern:

Be it known that I, REYNOLD JANNEY, a citizen of the United States, residing at New York, in the county of New York and 5 State of New York, have invented certain new and useful Improvements in Universal Joints, of which the following is a specification.

This invention relates to universal joints 10 among the objects of the invention being the provision of an article of this character which is strong, compact, and effective in action.

The device possesses other features of advantage and novelty which with the foregoing will be stated at length in the following description wherein I will set forth in detail that one of the several convenient forms of embodiment of the invention which I 20 have selected for illustration in the drawings accompanying and forming part of the present specification, this disclosure being provided to enable those skilled in the art to practice the invention. From this it will be 25 clear that I do not restrict myself to said disclosure; I may depart therefrom in several respects within the scope of the invention defined by my claims.

Referring to said drawings: Figure 1 is 30 a vertical sectional view of a universal joint involving my invention. Fig. 2 is a similar view with the parts in different positions. Fig. 3 is a horizontal section of said joint, and, Fig. 4 is a cross section of the same. 35 Fig. 5 is a transverse section in a plane through the lower of the rectangular bushing blocks shown in Fig. 4.

Like characters refer to like parts throughout the several views.

40 The joint comprises in its make up a shaft, a ring surrounding said shaft, and a cruciform coupling member for operatively uniting the two parts. Said shaft is preferably rotative about a fixed axis while the 45 ring is rotative with the shaft being preferably supported by independent bearing means which may be of any suitable nature. As will hereinafter appear the ring shown in the drawings in addition to its rotary 50 movement is tiltable or oscillatory, but this is not necessary in all cases.

A shaft such as meets my requirements is that denoted by 2 which as represented, is provided with a closed yoke 3 between the 55 ends thereof; this yoke is not always essen-

tial (although advantageous), in that other means may be provided for sustaining two opposite trunnions of a cruciform member, or trunnion block, such as that denoted in a general way by 4 although one of a different nature would answer the required conditions. The third principal member of the joint may also vary as to form, the ring 5 being satisfactory in this connection. Said coupling member 4 as already indicated has 60 two of its opposite trunnions supported by the shaft 2, the other two opposite trunnions thereof being sustained by the ring 5. Said cruciform coupling member 4 as illustrated, 65 consists of two transversely disposed parts 6 and 7, the part 6 having a substantially central portion (constituting the body of said coupling member), from which extend oppositely the approximately duplicate trunnions 8 pivotally supported within the 70 ring 5 as will hereinafter appear. There is shown driven through the substantially central portion of the part 6, the part 7 shown as consisting of a cylindrical pin, 75 the terminal portions of which present two 80 opposite trunnions rotatively supported by the sides of the yoke 3. Said sides have openings to receive the bushings 9 in which are fitted the terminal or trunnion portions of the member or pin 7, being represented as 85 rigidly held in place by the pins 10. The two parts 6 and 7 of the coupling member 4 are held securely together by the rivet 11 extending through registering holes therein, so that in effect the said coupling member 90 is an integral structure and in practice could be.

The interior of the ring is apertured at diametrically opposite points as at 12 to receive the enlarged portions of the sides of 95 the yoke 3. Said ring is further shown provided internally thereof, with inwardly-extending projections 13 disposed in approximately diametrically opposite pairs, a bushing block 14 being situated between each 100 pair of projections. Said blocks are externally rectangular, and their opposite sides fit against the flat walls of said projections to thus key said bushing blocks in place. To further prevent movement of said bushing blocks the screws 15, of which there are 105 four, may be provided; each screw being threaded partly into a projection and partly into a bushing block by reason of which motion of said blocks in all directions is pre- 110

vented. Said bushing blocks are cylindrically bored to receive for oscillation the trunnions of the part 6 as already described.

On reference to Fig. 4 it will be perceived that there are intervals or clearance spaces between the body portion of the coupling member or trunnion block 4 and the sides of the yoke 3 and that there are practically similar spaces between said body portions and the bushing blocks 14 which is one simple way of securing a prime advantage to which I will hereinafter refer. It is assumed that the axis of rotation of the shaft 2 coincides with the axis of rotation of the ring 5 but from a variety of causes such for instance as an error in workmanship or because of wear or changes in position due to stress, this is not always so. In view of the clearance or relief spaces to which I have referred, I provide for a comparatively slight amount of relative lateral motion of the shaft 2 and ring 5, so that notwithstanding the fact that their axes be out of coincidence, accurate operation of the joint will follow. It will be evident therefore that when I state that the shaft 2 rotates about a fixed axis I mean that said axis is rigid, although it may be slightly moved, the same applying to the ring 5. In any event the deviation of the shaft or the ring from its normal axis is at best, very slight but as will be clear I have provided for the same without any ill effects following.

As already set forth the ring 5 is rotary. In the construction described it has in addition a swinging or oscillatory movement being supported for this purpose by what is known as a "tilting box" 16 which constitutes a convenient means for such purpose although one of a radically different kind might be employed instead; in fact the bearing for the said ring could be stationary. This tilting box is a common device in a hydraulic variable speed gear, and it has several positions, being usually movable oppositely from its neutral or zero position by hand. As the purpose of such a device is so well known it is needless for me to describe the same. Said tilting box is shown consisting of a shell supported for oscillation by the pivots 16' and the means illustrated for operating said tilting box are a screw and a nut as will hereinafter appear. In the organization shown the axis of oscillation of said tilting box is practically coincident with the longitudinal axis of the pin 7.

When the ring 5 is used in connection with a tilting box it is adapted for connection with the pistons of such a hydraulic variable speed gear, so that said speed gear can be brought to a state of rest or its speed regulated, and necessary changes in direction accomplished, by the movement of the tilting box to a neutral position or to positions opposite said neutral position, it being

clear that when the tilting box is oscillated corresponding movements of the ring 5 follow, so that the conditions pointed out can be secured. These pistons or their equivalents, forming no part of the present invention, are not herein illustrated; their stems may be connected with the ring in any one of several different ways. The illustration pointed out is merely one use to which the ring 5 or its equivalent can be put. 75

The ring 5 is shown having on its rear side the annular rabbet or groove 17 and in the same is fitted the bearing ring 18. The ring 19 surrounds the ring 18 and is supported in the tilting box 16, and between the opposite faces or races of the two rings 18 and 19 are interposed anti-friction rollers 20 held in a cage 21, said rollers 20 being provided to take up side or diagonal thrust. The rollers 22 take up end thrust being as shown of conical or tapering construction and being adapted to bear against inclined faces or races on the ring 18 already described and on the ring 23 set into a rabbet or groove in the rear portion of the tilting box 16; said rollers 22 are carried in a cage 24.

The screw 25 rotates in the construction shown, about a fixed axis and its threaded portion receives the nut 26, said nut being shown provided with outwardly extending journals 27 pivotally fitting bearing openings in the duplicate blocks 28 disposed for sliding movement in longitudinally-extending slots in the arms 29 projecting rearwardly from the tilting box. By the operation therefore of said screw the tilting box can be moved oppositely from its neutral position standing when in said neutral position approximately perpendicularly. It will be understood that as the tilting box 16 is adjusted angularly the ring 5 is similarly adjusted. The trunnion block or cruciform coupling member 4 connects the shaft 2 and ring 5 for relative universal movement and also provides a means whereby said ring can be supported independently of said shaft, the tilting box 16 constituting conveniently such an independent support. 110

What I claim is:

1. The combination of a ring having interiorly thereof projections arranged in diametrically opposite pairs, bushing blocks externally rectangular fitted between the respective pairs of projections, screws threaded into the respective bushing blocks and projections to prevent motion of said bearing blocks in all directions, a shaft extending through, and having a closed yoke within, said ring, and a cruciform trunnion member, two opposite trunnions of which are fitted pivotally in said bushing blocks and the other two opposite trunnions of which are fitted in the branches of said yoke. 125

2. The combination of a ring having in- 130

- teriorly thereof projections arranged in dia-
metrically opposite pairs, rectangular bush-
ing blocks situated respectively between
each pair of projections, the inner faces of
5 the projections being flat to be engaged by
the bearing blocks to prevent the bearing
blocks from rotating, a shaft extending
through, and having a closed yoke within,
said ring, and a cruciform trunnion member,
10 two opposite trunnions of which are piv-
otally fitted in said bushing blocks, and the
other two opposite trunnions of which are
pivotally fitted in the branches of said yoke,
and means for keying said bushing blocks in
position. 15

In testimony whereof I affix my signature
in presence of two witnesses.

REYNOLD JANNEY.
